FOLDABLE TABLE

Floyd Frederick O'Toole, L'Anse, Mich., assignor
of two-fifths to Leo J. Brennan, L'Anse, Mich.

Application January 25, 1939, Serial No. 252,812

2 Claims. (Cl. 311—82)

The invention relates to a table and more particularly to tables having foldable legs, commonly known as card tables.

The primary object of the invention is the provision of a table of this character, wherein the legs thereof may be folded against the under side of the table top and are associated with each other so that when swinging any one of the legs to or from an extended or supporting position the remaining legs will be simultaneously moved and thus enabling convenient and easy setting up or folding of such table with dispatch.

Another object of the invention is the provision of a table of this character, wherein the legs when in supporting position will be latched so as to eliminate the collapsing or folding of the table or the legs thereof during the use of the same, the means for the simultaneous operation of the legs on manually swinging any one of the same is of novel construction.

A further object of the invention is the provision of a table of this character, wherein the assembly of the means for operating the legs simultaneously with each other, the legs and the braces for said legs are assembled in a unique manner so that the structural make-up of the table will be compact, particularly when in a folded position, thus enabling the convenient storage of such table in minimum space and particularly in restricted places.

A still further object of the invention is the provision of a table of this character, which is simple in its construction, thoroughly reliable, efficient and practical in operation, strong, durable, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is a bottom plan view of a table constructed in accordance with the invention showing the legs folded against the under side thereof and such table being partly broken away for illustrating details of construction.

Figure 2 is a sectional view on the line 2—2 of Figure 1 looking in the direction of the arrows, certain parts being broken away and the legs disclosed folded by full lines and by dotted lines extended.

Similar reference characters indicate corre-

sponding parts throughout the several views in the drawing.

The invention is adaptable for the construction of various types of tables, more particularly adaptable to tables commonly known as card tables in which the legs are foldable against the under side of the table top so that the table may be folded into compact condition for the storage thereof in the least possible space when such table is not in use and the table illustrated is of that type.

The table in the present instance comprises a top 5 of substantially equilateral or square shape, although it may be of other shape, and is constructed from any suitable material, being finished or covered at the upper side thereof in a manner as may be further desirable. Marginally of the top 5 is a flange-like rim 6 which is continuous throughout the sides of the said table while disposed inwardly in parallel relation to the rim which protrudes from the under side of the top are strips 7, these being disposed parallel with the said rim at all sides of the top 5 to provide a channel or groove 8 between the said rim and strips. The strips 7 are slightly separated at adjacent ends to each other. At the separated ends of the strips 7 and mounted at the under side of the top 5 within the channel or groove 8, that is to say, approximating four corners of the table top 5 are guide pulleys or rollers 9 over which is trained a flexible endless steel tape 10 adapted for movement for a purpose presently described.

The table shown is provided with swinging legs 11, these pivoted at 12 next to the four corners of the top 5 for swinging movement inwardly of and in parallel relation to the strips 7 so that such legs can be folded against the under side of the table or extended to supporting position, being all mounted in the same manner. Thus each swings in the same direction in relation to the periphery of the table from their individual corners and lie substantially parallel with the said strips 7 when they are folded against the under side of the table top.

Associated with the tape 10 and lying within the channel or groove 8 are sprocket chain sections 13, one for each side of the table top and common to a leg at such side, while meshing with these sections 13 are sprocket gears 14, each being fixed to a journal 15 in a bearing 16 therefore built in the rim 6 and strip 7 adjacent thereto, the said bearing 16 being of a character to afford a clearance for the meshing engagement of the sprocket gear 15 with its companion chain 55

section 13. The journals 15 have fixed thereto swinging braces 17, each having a slidable stud connection 18 with a leg 11, the latter being provided with a slot 19 in which is slidably fitted 5 the stud connection 18. The slot 19 extends longitudinally of the leg 11 and has an offset end portion 20 in which the stud connection 18 comes to rest when the said leg is in extended or table-supporting position for the latching of the brace 10 17 with the leg to avoid accidental folding of said leg when the table is set up for use. The brace 17 operates the gear 14 meshing with the chain section 13 when a selected leg 11 is swung, either inwardly against the under side of the 15 table top 5 or outwardly to an extended position, and this selected leg when operated imparts similar movements to the remainder of the legs so that they will be simultaneously folded or unfolded similarly to the movement of the selected leg when manually moved. On the swinging of a selected leg 11 inwardly, the latch connection of the brace 17 therewith will be broken or disrupted and this occurring with all of the braces when the said legs are extended to supporting position so that all of the legs will be simultaneously folded with each other.

In the operation of the table, it is only required of an operator to merely swing inwardly any one of the legs and the other legs move simultaneously therewith, this action being had both for the folding of the legs or the unfolding thereof. It may be necessary that one of the braces 17, that is to say, the selected leg to be operated, be manually unlatched from engagement therewith 30 so that the other legs will be caused to automatically unlatch from the braces and such legs simultaneously folded inwardly against the under side of the table top.

What is claimed is:

1. In a table, a top, pulleys arranged at spaced points on the under side of said top, legs close to the pulleys and pivoted to the top for folding inwardly against the same, an endless tape movable over the pulleys and having short flexible sprocket chain sections between the said pulleys, sprocket gears fixedly journaled in place between the legs for meshing with the sprocket chain sections, respectively, and a swinging one-piece 10 brace for operating each sprocket gear and slidably fitted to a companion leg whereby when one brace operates its sprocket wheel and chain section, the other chain sections are operating the other gears and attached braces and moving all 15 of the legs in unison with each other.

2. In a table, a top, pulleys arranged at spaced points on the under side of said top, legs close to the pulleys and pivoted to the top for folding inwardly against the same, an endless tape movable over the pulleys and having short flexible sprocket chain sections between the said pulleys, sprocket gears fixedly journaled in place between the legs for meshing with the sprocket chain sections, respectively, a swinging one-piece brace 25 for operating each sprocket gear and slidably fitted to a companion leg whereby when one brace operates its sprocket wheel and chain section, the other chain sections are operating the other gears and attached braces and moving all 30 of the legs in unison with each other, and lugs formed on the braces, the said legs having slots longitudinally disposed therein, each with an offset end and slidably receiving the lugs for limiting the swing of the legs and relieving strain 35 from the pivotal connections between the latter and the top.

FLOYD F. O'TOOLE.
